UNITED STATES PATENT OFFICE.

LUTHER M. SCOTT, OF AUBURN, MAINE.

NECKTIE.

Application filed October 14, 1920. Serial No. 416,785.

To all whom it may concern:

Be it known that I, LUTHER M. SCOTT, a citizen of the United States, residing at Auburn, in the county of Androscoggin and 5 State of Maine, have invented certain new and useful Improvements in Neckties, of which the following is a specification.

This invention relates to improvements in neck ties.

10 An important object of this invention is to provide a neck tie having novel means whereby the necessity of pulling and tugging at the same is avoided when applying the tie.

15 A further object of the invention is to provide a neck tie having novel means whereby the same is securely held in position while being worn.

20 A further object of the invention is to provide a neck tie having a lining which may be conveniently detached or removed when it is desired to press the tie.

25 A further object of the invention is to provide a tie of the class described which is knotted strictly by hand and is, therefore, neat looking when applied.

Other objects and advantages of the invention will be apparent during the course of the following description.

30 In the accompanying drawings—

Figure 1 is an elevation of the improved tie,

Figure 2 is a similar view of the improved tie arranged in bow formation,

35 Figure 3 is a fragmentary elevation of the improved tie open, parts thereof being shown in section, and

Figure 4 is a detail sectional view through the improved tie, illustrating the means employed for detachably connecting the lining to the tie.

40 In the drawings, wherein for the purpose of illustration is shown a preferred embodiment of the invention, the numeral 5 designates the improved tie which comprises wide and narrow tie sections 6 and 8 adapted to be formed into a four-in-hand knot as illustrated in Figure 1, or arranged in bow formation as illustrated in Figure 2.

45 As a result of continued use of a tie, the lining of the same becomes creased as does the tie itself. The creases in the lining do not in all cases conform to the creases in the tie so that it is impracticable to press 55 the creases out of the lining. To overcome

this difficulty, I have provided each of the sections 6 and 8 with a lining 10 which is capable of being detached when it is desired to press the tie. As illustrated in Figure 4, the lining 10 is provided at its inner end 60 with a buttonhole 12 adapted to receive a button 14 secured within the tie to one side of the same. When it is desired to remove the lining 10, the button 14 is disengaged from the adjacent end of the section so that 65 the lining may be separated from the tie. The tie and lining may then be pressed separately so that the creases in the same will be removed. After the lining of the tie and several sections of the tie have been separately pressed, the lining may again be arranged within the tie in the proper manner.

70 The sections 6 and 8 of the improved tie are connected by means of an elastic strap 16 having its end portions provided with 75 buttons 18 and 20 which are adapted to be passed through buttonholes 22 in the end portions of the sections 6 and 8. The elastic section 16 is, of course, adapted to be positioned between the inner and outer folds 80 of the collar as is the intermediate portion of the usual four-in-hand tie. However, in the case of a low collar, the elastic section 16 may be somewhat narrow, while in the case of a high collar, the elastic section may 85 be wider. In tying a four-in-hand tie, as illustrated in Figure 1, the elastic section 16 is arranged between the inner and outer folds of the collar subsequent to connecting the rear ends of the sections 6 and 8 to the 90 ends of the elastic section 16 by means of the buttons and buttonholes. In the practical use of the device, the rear ends of the sections 6 and 8 will extend about two or three inches from the front of the collar. When 95 tying the tie, as illustrated in Figure 1, either of the sections may be moved independently of the other thereby relieving the collar of the strain incident to the pulling of the tie through the same. One of the sections of the tie may be adjusted independently of the other, since the intermediate section 16 is capable of yielding to a limited degree.

100 When removing the tie it is not necessary to untie the knot of the same since the ends of the sections 6 and 8 may be disconnected from the elastic section 16 by disengaging the buttons 18 and 20 from the buttonholes 22. This, of course, may be done by pulling 110

the ends of the elastic section to the front of the collar.

As illustrated in Figure 2, the improved tie may be arranged in bow formation and when so arranged may remain tied even when not in use. When it is desired to position the bow 30 about the collar, it is merely necessary to connect the ends of the sections 6 and 8 to the ends of the elastic section 16.

With reference to the foregoing description, taken in connection with the accompanying drawings, it will be appreciated that a neck tie constructed in accordance with this invention may be readily and conveniently applied without distorting or tearing the collar. Since the intermediate section 16 is capable of yielding, no great amount of pulling or tugging at the tie is necessary when adjusting the same. The intermediate section may be of a width suitable to the size of the collar.

The invention is subject to such minor changes in arrangement and construction of parts as will remain within the spirit of the invention and the scope of what is claimed.

Having thus described the invention, what is claimed as new is:

1. A necktie comprising a pair of sections one adapted to be knotted about the other 30 in the usual manner whereby one section may be pulled through the knot to adjust the tie about a collar, an elastic band connected to one of the sections at the upper end thereof, and means separably connecting the other 35 end of the elastic band with the other section at such point that when the knot is formed said separable connections will be located above, at one side of, and adjacent to said knot and whereby said separable 40 connection may be manipulated to permit of application and removal of the tie to and from the collar after the knot has been initially tied and without disturbing said knot.

2. The combination with a necktie having 45 a tubular apron portion, and a lining arranged removably therewithin, of means separably connecting the lining with one wall of the tubular apron whereby to suspend the lining within the apron.

In testimony whereof I affix my signature.
LUTHER M. SCOTT. [L. S.]
